UNITED STATES PATENT OFFICE

143,876

DESIGN FOR A SMOKER'S STAND

William C. Panzer, Chicago, Ill.

Application April 12, 1945, Serial No. 118,964

Term of patent 14 years

(Cl. D85—2)

To all whom it may concern:

Be it known that I, William C. Panzer, a citizen of the United States residing in Chicago, Cook County, Illinois, have invented a new, original, and ornamental Design for a Smoker's Stand, of which the following is a specification, reference being had to the accompanying drawing, forming a part thereof.

The stippled portions represent a pebbled or wrinkled flat-paint surface.

I claim:

The ornamental design for a smoker's stand, substantially as shown and described.

WILLIAM C. PANZER.
